UNITED STATES PATENT OFFICE.

JOHN M. CRAIGO, OF HARTFORD, CONNECTICUT.

ATTACHMENT FOR TEETH.

Application filed August 3, 1925. Serial No. 47,987.

This invention relates to means for attaching artificial bridges, plates, dentures, or other orthodontia appliances to permanent or natural teeth in the mouth.

5 The aim of the invention is to provide an attachment of this sort having various features of novelty and advantage and which is particularly characterized by its extreme simplicity in construction, the ease and facility with which it may be constructed and applied, and its effectiveness in use.

A more particular aim of the invention is to provide an improved attachment by means of which the denture or bridge work may be 15 held in proper relation to the permanent teeth with which it is associated, the artificial teeth or bridge work being held thereby against tilting and pivotal movements while, at the same time, the bridge work is so supported that the portion of the gums which it engages is subjected to the proper action so that the gums are maintained in 20 good condition.

25 A further aim of the invention is to provide a simple and effective attachment which may be readily removed and replaced when it is desired to clean, repair or perform other necessary operations upon the appliance.

30 A further object of the invention is to provide an attachment which may be readily applied to any of the permanent teeth in the mouth without in any way mutilating or damaging such teeth. My attachment may be correctly fitted to teeth which are irregular or abnormally inclined.

35 A further aim of the invention is to provide an improved attachment which is very neat in appearance.

40 My improved arrangement is such that crevices, cracks or the like in which particles of food or other foreign matter may lodge are substantially eliminated, and undue stress on the permanent teeth to which the attachment is applied is avoided. A further 45 object of the invention is to provide an improved arrangement wherein the clasp (or clasps) forming part of the attachment is held against accidental withdrawal from the permanent tooth with which it is associated while, at the same time, the clasp may move 50 up and down on the tooth so that stress on the permanent tooth is broken and the portion of the gums lying beneath the plate or bridge work will be maintained in proper 55 condition.

Other objects will be in part obvious and in part pointed out more in detail herein-after.

The invention accordingly consists in the features of construction, combination of elements and arrangement of parts which will be exemplified in the construction herein-after set forth, and the scope of the application of which will be indicated in the appended claims.

In the accompanying drawings, wherein I have shown, by way of illustration, one embodiment which the present invention may take:

Figure 1 is a front view showing a denture 70 or appliance attached to two permanent teeth;

Fig. 2 is a perspective view showing a clasp constructed in accordance with the present invention in position to be slipped 75 over the crown;

Fig. 3 is a sectional view through the crown and clasp applied thereto, the tooth which the crown caps being in elevation, this view being taken substantially on line 3—3 80 of Fig. 1; and

Fig. 4 is an enlarged detail view taken through one arm of the clasp substantially on line 4—4 of Fig. 1, the crown being shown 85 in outline.

In these drawings, I have shown a bridge carrying four artificial teeth and having, at each end, a clasp respectively associated with two crowned permanent teeth, but it is to be understood that this showing is by way 90 of exemplification only and it is not to be taken as restrictive of my conception, it being obvious that the denture or orthodontia appliance may be of any desired form depending upon conditions and that the denture may be held in place by a single clasp. For purposes of brevity and convenience in description and claiming, the orthodontia appliance, plate or denture will be referred 95 to as a bridge, it being understood that this term is applied in its generic sense.

Referring to the drawings in detail, *a* denotes one of the jaws of the mouth; *b*, permanent teeth; and *c*, crowns for the permanent teeth. Between the permanent teeth are artificial or removable teeth *d* fixed to a plate or bridge *e* having at each end a clasp *f*.

Each of the clasps may be in the form of a U-shaped or parti-circular band adapted to 110

2
partially encircle the crown on the permanent teeth. In the present instance, each clasp is shown as having a pair of arms 10, 10, adapted to closely straddle a crown, the 5 clasp, by preference, being made of a suitable resilient material so that the arms may spring slightly apart when slipping the clasp onto a crown or removing the same therefrom and so that the arms will hug the 10 crown when the clasp is in position. Each of the clasps may have a tang or wing 11 by means of which it is secured to the bridge e. or each clasp may be formed integrally with the plate or bridge.

15 In accordance with the present invention, each arm of a clasp is provided with a vertical groove 12, and these grooves are adapted to receive projections 13 on the opposite sides of the crown. In the present illustrative disclosure, each of the grooves 12 has, at its lower end, a shoulder 14 inclined inwardly and downwardly, and the underside of the cooperating projection 13 is similarly inclined. Furthermore, the arrangement is 20 such that the clasp may move up and down on the teeth with the projections 13 engaging in the grooves 12, the advantage of this being that stress on the permanent teeth surrounded by the clasp is broken and the 25 bridge may rest upon the gums between the permanent teeth whereby the gums will be properly manipulated or massaged to retain the same in good condition. In the drawings, the grooves 12 are shown as being 30 open at their upper edges so that the clasp, when in the position illustrated in Fig. 4, may move or slide downwardly on the crown. At the same time, the projection 13 limits the 35 upward movement of the teeth and prevents 40 accidental withdrawal of the clasp from the crowns. However, with the arrangement described, when it is desired to remove the bridge, this may be readily done by pulling up on the bridge whereupon the projections 45 will cam the arms apart so that the clasp will slip over these projections. By preference, each arm is further provided with a second recess or depression 15, and these depressions are vertically aligned or immediately 50 beneath the grooves 12 and are open at their lower edges. The purpose of these 55 depressions 15 is to facilitate the positioning of the clasp about the crowns, it being observed that, when the clasps are moved down 60 into position on the crowns, the depressions 65 will be received by the projections 13 so that the clasps are properly located and the projections will cam the arms apart so that the clasps will slip over the projections until 70 these projections are received by the grooves 12.

For the purpose of insuring against tilting or pivotal action of the clasp relative to the crown which it surrounds and, at the same time, guide the clasp in its movements

up and down on the crown, each arm of the clasp is provided with a channel 20 adapted to respectively receive or accommodate vertically extending ribs 21 on the opposite sides of the crown. By preference, each of 70 these channels is uniform throughout its length and extends from the upper to the lower edge of the arm in which it is located. The ribs 21 are at least as long as the channels and correspond in cross section to the 75 channels. The projections 13 and the long projections or ribs 21 of the crowns may be economically formed by bending the metal of the crown outwardly by means of suitable dies.

80 I claim as my invention:

1. In combination, a tooth element having on, at least, one side a projection, and a clasp having a pair of resilient arms one, at least, of which has a recess adapted to receive said projection, said arm having at its lower edge a recess vertically aligned with said first recess, said second recess being open at its lower end and having an inclined wall adapted to engage said projection when 85 positioning the clasp in place whereby said arms are cammed apart.

2. In combination, a crown having a projection on each of two of its opposite sides, and a clasp having a pair of resilient arms hugging said crown and each provided with a recess spaced from its lower edge, each arm also having a recess at its lower edge vertically aligned with a respective first mentioned recess, each of the second mentioned recesses being open at its lower end and having an inclined wall, substantially as described.

3. In combination, a tooth element, and a clasp element having a pair of arms straddling said tooth element and adapted to be slipped into and out of place thereon, one of said elements having an elongated vertically extending groove provided at one end with a cam surface, and the other of said elements having a projection vertically movable in said groove and adapted to be detached therefrom, said clasp having slideable vertical movement on said tooth element, and said cam surface and projection being adapted to interengage to limit the movement of the clasp towards the upper end of the tooth element whereby the clasp is held against accidental withdrawal.

4. In combination, a crown having a projection on one of its side faces, and a clasp having a pair of arms straddling and hugging said crown, one of said arms having a vertically extending groove with a cam surface at its lower end, said projection being relatively shorter than said groove and being adapted to slide therein, said cam surface being adapted to engage said projection and thereby prevent accidental withdrawal 125 of the clasp from said crown, and said clasp 130

having sliding movement on the crown with the projection engaging in said groove.

5. In combination, a crown having a projection on each of its opposite sides, and a clasp having a pair of arms straddling said crown and each provided with a groove open at its upper end and with a cam surface at its lower end, said grooves being adapted to respectively receive said projections, and said clasp having movement relative to said crown with the projections engaging in said grooves, said arms further having in their lower edges and respectively alined with said grooves recesses adapted to respectively accommodate said projections when slipping the clasp into place on said crown.

6. In combination, a tooth element having a projection on one side, and a clasp having a pair of arms straddling said tooth element, one of said arms being provided with a groove extending downwardly from the upper edge of the arm and terminating short of the lower edge thereof, the inner end of said groove having an inclined surface, said clasp having movement relative to said tooth element with the projection engaging in said groove, said arm further having in its lower edge and alined with said groove a recess adapted to accommodate said projection when slipping the clasp in place on said tooth element.

7. In combination, a crown having a projection and a rib on its sides, and a clasp having a pair of arms straddling said crown and one provided with a vertically extending elongated groove with a cam surface at its lower end, one of said arms having a channel, said groove receiving said projection and said channel receiving said rib, and said clasp having movement relative to said crown with the projection and rib respectively engaging in said groove and channel.

8. In combination, a crown having on each of two of its opposite sides a projection and a relatively long vertical rib, and a clasp having a pair of arms straddling said crown and each arm provided with a groove extending downwardly from the upper edge of the arm and terminating short of the lower edge thereof, the inner end of each

groove having an inclined surface, said projections having camming surfaces respectively engaging said inclined surfaces of said grooves, each of said arms also having a channel or groove adapted to receive a respective rib, each of said channels extending from the upper to the lower edge of the arm in which it is located and each channel corresponding in cross section to the respective rib which it receives.

9. In combination, a crown having on each of two of its opposite sides a projection and a relatively long vertical rib, and a clasp having a pair of arms straddling said crown and each arm provided with a groove extending downwardly from the upper edge of the arm and terminating short of the lower edge thereof, the inner end of each groove having an inclined surface, said projections having camming surfaces respectively engaging said inclined surfaces of said grooves, each of said arms also having a channel or groove adapted to receive a respective rib, each of said channels extending from the upper to the lower edge of the arm in which it is located and each channel corresponding in cross section to the respective rib which it receives, said arms further having in their lower edges and respectively alined with said grooves recesses adapted to respectively accommodate said projections when slipping the clasp into place on said crown.

10. A clasp for attaching a bridge to a tooth and comprising a pair of resilient arms adapted to straddle the tooth and each having a groove on its inner face open at its upper end and having a cam surface at its inner end, each arm also having a recess at its lower edge and alined with a respective groove.

11. A clasp for attaching a bridge to a tooth and comprising a pair of resilient arms adapted to straddle the tooth and each having a groove on its inner face open at its upper end and having a cam surface at its inner end, each arm having on its inner face a channel extending from edge to edge of the arm.

JOHN M. CRAIGO.
